(57) **CLAIM**

The ornamental design for an electric cleaning brush, as shown and described.

DESCRIPTION

FIG. 1 is a front, right and bottom perspective view of an electric cleaning brush, showing my new design;

FIG. 2 is a rear, left and bottom perspective view thereof; FIG. 3 is a front perspective view thereof, shown in an environment of use;

FIG. 4 is a front view, shown with environment removed;

FIG. 5 is a rear view thereof;

FIG. 6 is a left side view thereof;

FIG. 7 is a right side view thereof;

FIG. 8 is an enlarged top plan view thereof;

FIG. 9 is an enlarged bottom plan view thereof; and,

FIG. 10 is an enlarged view of portion "10" shown in FIG. 3.

In the figures, the dash-dash style of broken lines illustrates portions of the brush, and form no part of the claimed design. Additional broken lines illustrating a brush head in FIG. 3 illustrate environmental subject matter, and form no part of the claimed design. The dot-dash style of broken lines shown in FIGS. 3 and 10 illustrates enlarged view indicators, and forms no part of the claimed design.
